DESIGN FOR A BRACELET WATCH

David Ornstein, New York, N. Y.

Application January 27, 1940, Serial No. 89,765

Term of patent 7 years

To all whom it may concern:

Be it known that I, David Ornstein, a citizen of the United States, residing at 129 West 22nd Street, New York, in the county of New York and State of New York, have invented a new, original, and ornamental Design for a Bracelet Watch, of which the following is a specification, reference being had to the accompanying drawing, forming a part thereof.

In the drawing:

Fig. 1 is a side elevational view showing my new design;

Fig. 2 is a plan view;

Fig. 3 is a partial end elevation from the left side of Fig. 1 showing the watch dial on my device, and

Fig. 4 is a partial end elevation from the right side; Figs. 3 and 4 showing portions as indicated.

I claim:

The ornamental design for a bracelet watch, as shown.

DAVID ORNSTEIN.
